(57) **CLAIM**

The ornamental design for a storage cabinet, as shown and described.

DESCRIPTION

1. Storage cabinet

Fig. 1.1 is a perspective view of a storage cabinet according to the present invention.

Fig. 1.2 is a front elevational view of the storage cabinet of Fig. 1.1.

Fig. 1.3 is a front elevational view of the interior of the cabinet of Fig. 1.1 as viewed with the doors open.

Fig. 1.4 is a fragmentary perspective view of the base of the storage cabinet of Fig. 1.1 viewed from the front of the cabinet looking downward.

Fig. 1.5 is a perspective view of the storage cabinet of Fig. 1.1 showing a side and the front of the cabinet.

Fig. 1.6 is plan view of the bottom of the storage cabinet of Fig. 1.1.

Fig. 1.7 is a front elevational view of the storage cabinet of Fig. 1.1.

Fig. 1.8 is a fragmentary side elevational view of the upper portion of the storage cabinet of Fig. 1.1.

Contemporary cabinet comprising an upper part measuring 135 cm×88 cm, 47.5 cm deep, supported by a sub-base made up of six cylindrical columns with a diameter of 80 mm made of clear translucent polymethyl methacrylate being 74 cm high and resting on a base which is 135 cm long×49.5 cm wide×5 cm high; the total height is 164.50 cm; the upper outer part is decorated with twelve inclusions incorporated in the mass; the cabinet opens by means of two equal flaps; the inner part consists of a body comprising sixteen drawers, each decorated with an inclusion; the set is lacquered in matte black.
